UNITED STATES PATENT OFFICE.

CHARLES R. BARRETT, OF CHICAGO, ILLINOIS.

MACHINE FOR FORMING LOOPS ON COIL-SPRINGS.

971,238.

Specification of Letters Patent. Patented Sept. 27, 1910.

Application filed February 13, 1909. Serial No. 477,755.

To all whom it may concern:

Be it known that I, CHARLES R. BARRETT, a citizen of the United States of America, and a resident of Chicago, in the county of 5 Cook and State of Illinois, have invented certain new and useful Improvements in Machines for Forming Loops on Coil-Springs, of which the following is a specification.

10 This invention relates to a mechanism for forming attaching loops or eyes on the ends of coiled wire springs, and has for its object to provide a simple and efficient mechanism for effecting such operation in a ready, rapid 15 and accurate manner, all as will hereinafter more fully appear.

In the accompanying drawings:—Figure 1 is a front elevation illustrating the general arrangement of the mechanism. Figs. 2, 3, 20 and 4 are detail elevations showing the different steps in the formation of the loop or eye on the end of a spring. Fig. 5 is a detail perspective view of a coiled spring on which attaching loops have been formed by the 25 mechanism.

Similar numerals of reference indicate like parts in the several views.

Referring to the drawings, 1 represents the supporting frame or standard having a 30 bearing in which turns the main shaft or arbor 2 of the mechanism, said shaft receiving motion through a gear wheel 3, or the like, from a suitable power source.

4 is a hub secured to the arbor 2, near 35 its forward end and provided with a radial bending jaw 5, which has traveled in a circular path and has its forward end made acute as shown in order to more effectively engage an end convolution of the spring operated on in bending said convolution into 40 an attaching loop in a manner hereinafter more fully set forth.

6 is the work-supporting head of the 45 mechanism and upon which the end of the coiled spring is supported in the manner hereinafter set forth during the loop forming operation. The main body of said head is carried by the main frame and is made adjustable thereon by a holding bolt 7, and 50 segmental slot 8, so that the position of the hereinafter described rest and anvil bars may be changed with relation to the bending jaw 5, to present the end of the coiled spring operated on in a direction best suited to the 55 formation of a perfect loop, the degree of

such adjustment depending mainly on the resiliency of the metal in the spring.

9 is a rest piece or bar adjustably held by the aforesaid supporting head 6, and formed with a straight resting face for the coiled 60 spring operated on. Said face is in a plane tangential to the circular path of the bending jaw 5, aforesaid, and as shown in Figs. 1, 2, 3 and 4. 10 is an anvil piece or bar also adjustably held by the aforesaid supporting head 6 in parallel relation to the rest bar 9 aforesaid and formed with a curved anvil end in adjacent relation to the circular path of the bending jaw 5, and constituting a breast over which the loop of the 70 coiled spring is bent, as well as a stop for the end of said spring to insure its proper position in the apparatus.

11 and 12 are adjusting screws by which 75 limited adjustment is imparted to the respective bars 9 and 10 aforesaid.

13 is a rock lever fulcrumed on the arbor 2 aforesaid. One end of said lever has a position above the aforesaid rest bar 9 and is formed with a holding eye 14, in which is secured a detachable jaw 15 which as said end of the lever is depressed bears upon the coiled spring to hold the same firmly in place while the bending jaw 5 is forcing an end convolution of the spring into an angular relation to the body of the spring to constitute an attaching loop or eye. 16 is an adjustable connecting rod extending from the opposite end of the aforesaid rock lever 13 to a rock arm 17 secured to a 80 countershaft 18 journaled in the upper end of the frame or standard 1, as shown in Fig. 1.

19 is a secondary arm carried by the 85 countershaft 18, aforesaid.

20 is a cam carried by the arbor 2 and engaging the free end of the secondary arm 19, to impart movement to the holding jaw 15, through the intermediate connection above described, at intervals during the 90 operation of the apparatus.

21 is a spring extending from the rock lever 13 to the main frame 1 and adapted to impart movement to said lever in a direction opposite to that imparted by the aforesaid cam 20.

In the operation of the mechanism, the coiled spring to be looped is placed on the rest bar 9 with its end abutting against the anvil bar 10. With the continued rotation 110

of the arbor 2, the cam 20 rocks the lever 13 to bring its holding jaw 15 down upon the spring to firmly clamp the same in position. While so held, the bending jaw 5 in its circular travel engages the end convolution of the spring to bend the same over the anvil 10 into a substantially right-angle relation to the body of the spring and form the required attaching loop or eye, as shown.

10 Continued rotation of the arbor 2 releases the holding jaw 15, from its grip on the coiled spring, so that the same may be removed and replaced by another spring for a repetition of the above operations.

15 Having thus fully described my said invention what I claim as new and desire to secure by Letters Patent, is:—

1. Mechanism for forming loops on coil springs, comprising a bending jaw having continuous movement in a circular path, and an anvil and a rest arranged in adjacent tangential relation to the circular path of said bending jaw, substantially as set forth.
2. Mechanism for forming loops on coil springs, comprising a rotary bending jaw the point of which moves in a circular path, an anvil and a rest arranged in adjacent tangential relation to the circular path of the bending jaw, a holding jaw adapted to hold a coil spring on said rest, and means for moving said holding jaw into and out of engagement with said coil spring, substantially as set forth.
3. Mechanism for forming loops on coil springs, comprising a rotary bending jaw the point of which moves in a circular path, an anvil and a rest arranged in adjacent tangential relation to the circular path of the bending jaw, and means for adjusting the tangential relation of said anvil and rest, substantially as set forth.
4. Mechanism for forming loops on coil springs, comprising a rotary bending jaw the point of which moves in a circular path, an anvil and a rest arranged in adjacent tangential relation to the circular path of the bending jaw, a holding jaw adapted to hold a coil spring on said rest, means for moving said holding jaw into and out of engagement with said coil spring, and means for adjusting the tangential relation of said anvil and rest, substantially as set forth.
5. In a mechanism for forming loops on coil springs, the combination of a supporting frame, an arbor journaled in said frame, a bending jaw rotating with said arbor with its point moving in a circular path, a head secured to the supporting frame, a rest bar and an anvil bar secured in adjacent relation

on said head and in tangential relation to the circular path of the bending jaw, substantially as set forth.

6. In a mechanism for forming loops on coil springs, the combination of a supporting frame, an arbor journaled in said frame, a bending jaw carried by said arbor and moving in a circular path, a head secured to the supporting frame, a rest bar and an anvil bar secured in adjacent relation on said head and in tangential relation to the circular path of the bending jaw, a holding jaw, a rock lever fulcrumed on the arbor and carrying said holding jaw, a countershaft, arms on said countershaft, a connection between one of said arms and the rock lever, a cam on the arbor engaging the other arm of the countershaft, and a spring imposing movement on the rock lever in a direction opposite to that imposed by the cam, substantially as set forth.

7. In a mechanism for forming loops on coil springs, the combination of a supporting frame, an arbor journaled in said frame, a bending jaw carried by said arbor and moving in a circular path, a head secured to the supporting frame, means for effecting an adjustment of said head with relation to the circular path of the bending jaw, the same comprising in part an attaching bolt and segmental slot, a rest bar and an anvil bar secured in adjacent relation on said head, substantially as set forth.

8. In a mechanism for forming loops on coils springs, the combination of a supporting frame, an arbor journaled in said frame, a bending jaw carried by said arbor and moving in a circular path, a head secured to the supporting frame, means for effecting an adjustment of said head with relation to the circular path of the bending jaw, a rest bar and an anvil bar secured in adjacent relation on said head, a holding jaw, a rock lever fulcrumed on the arbor and carrying said holding jaw, a countershaft, arms on said countershaft, a connection between one of said arms and the rock lever, a cam on the arbor engaging the other arm of the countershaft, and a spring imposing movement on the rock lever in a direction opposite to that imposed by the cam, substantially as set forth.

Signed at Chicago, Illinois, this 11th day of February 1909.

CHARLES R. BARRETT.
